WINDOW GLASS GUIDE

David C. Bailey, Amesbury, Mass.

Application June 14, 1935, Serial No. 26,591

8 Claims. (Cl. 296—44.5)

This invention relates to that class of window glass guides generally used in automobile bodies, which are so constructed that they may be bent to an extent sufficient to enable them to be conformed to the curvature of the window frames in which the glass is mounted, an example of which is shown in my prior Patent No. 1,963,541 of April 1, 1933.

While the construction of said patent has been extensively employed and is satisfactory in many respects, yet there is a constant demand that costs be reduced, and, on account of the fact that some looseness must be permitted between the ends of the tongues formed in the sides of the channel and the edge beads, to permit movement of the tongues therein when the channel is bent, some difficulty has been encountered in mass production due to the fact that the edge beads sometimes become detached.

The objects of my present invention are to provide a construction of the character above referred to, which may be produced at a somewhat reduced cost, as compared with prior constructions of like character and with which the mechanical difficulty above referred to may be obviated.

I accomplish these objects by means of the constructions hereinafter described and illustrated in the accompanying drawing, in which:

Fig. 1 is a side elevation illustrating a form of my invention installed in a window frame.

Fig. 2 is a view, partly in cross section and partly in perspective, showing a preferred embodiment of my invention.

Fig. 3 is a cross sectional view of a slightly modified form thereof.

Figs. 4, 5, 6 and 7 are detail views of different parts of the construction.

Figs. 8 and 9 are combined cross sectional and perspective views of two modified forms of my invention.

Fig. 10 is a sectional view at line 10—10 of Fig. 9.

According to my invention I provide two side members each of which consists of a continuous edge portion 12 and a series of suitably spaced tongues 13, which are formed by providing a strip of thin metal of suitable width and cutting through the middle portion thereof in the zig-zag manner indicated in Fig. 6, so that the strip is cut into two pieces, each of which is then bent to provide a rolled edge portion 14 on the continuous portion and a right angularly disposed lip 15 on the end of each tongue, as shown in Fig. 7. I also provide a base strip 16 of

uniform width, each edge of which is turned up to provide a narrow flange 17, as shown in Fig. 4. I further provide a base reinforcing strip 18, both edge portions 19 of which are somewhat off-set, as shown in Fig. 5, and the distance between the edges thereof being somewhat less than the distance between the inner sides of the flanges 17.

These parts are then assembled by placing the tongues 13 of the side members against the inner sides of the flanges 17 of the base strip 16, with the lips 15 engaged with the inner side of the latter and extending inward and then placing the reinforcing strip 18 on the inner side of the base strip, so that the off-set portions 19 thereof extend over the lips 15, and then attaching the strip 18 to the base strip by spot welding, or other suitable or convenient means, the parts thus being arranged as shown in Fig. 2 or 3.

The edge portions of the strips 16 and 18 thus provide continuous grooves or recesses into which the lips 15 extend, the latter being held in position therein by the edge flanges 17, and the parts being so arranged that, while there is no substantial looseness between the tongues of the sides and the base sections, yet a slight sliding movement of the ends of the tongues, longitudinally of the grooves in which they are located, is permitted.

The inner surface of the channel thus formed is lined with suitable cushioning material, which consists of a strip 20, which may be adhesively connected to the base strip 18, and separate side strips 21, the edges of which are preferably clamped by the rolled-over edges 14 of the sides, as shown in Fig. 2. The outer surface of the sides may be partly covered by a narrow strip 22 of textile material, which is clamped by the edge 14 and extends for a short distance towards the bottom of the channel, as shown in Fig. 3.

With the above described construction, when the channel, as thus formed, is bent to conform to a curved window frame or casing, as shown in Fig. 1, the rolled edges 14 and the base members 16 and 18 may be bent sufficiently without difficulty. Bending of the edges 14 will, however, tend to cause the tongues 13 to be swung from their parallel to radial positions, as shown in Figs. 1 and 10, the lip portions 15 being moved slightly in the grooves formed between the bottom members, so that bending of the sides will be permitted without strain or buckling. The flanges 17 on the base section 16 are so narrow that, while they tend to prevent bending of this portion

of the channel, they do not appreciably affect it. As their only function is to hold the tongues in position in the grooves, the extent to which edge portions are bent to perform this function may 5 be less than that indicated in the drawing. The lips 15 also act to hold the sides in upright positions and after the channel is installed and the glass placed in position, the channel will function as efficiently as any other guide used in 10 this relation.

The strip 18 also reinforces the base strip 16, so that both may be formed from very thin metal and, as there is no waste of metal in the formation of the sides, an actual saving in metal 15 may be made over my said prior construction.

In Figs. 8 and 9 two modifications of my invention are illustrated. In Fig. 8, a base member 25 is shown the edge portions 26 of which are rolled about reinforcing wires 27, and the side 20 members 28 are provided with tongues 29, as before described, and the end portions 30 of said tongues are bent about the exterior of the rolled or beaded edge portions, so that they are securely held in engagement therewith, but slight-movement 25 of the tongues on the beaded edges of the base member is permitted when the channel is bent, in substantially the same manner as before described in reference to the form shown in Fig. 2. The exterior of the sides are preferably covered 30 with thin textile material 31, which is adhesively secured to the strip of material before it is cut to form the tongues, as shown in Fig. 6, so that the cloth will be cut between adjacent tongues and will not interfere with the bending 35 operation. A narrow textile strip 32 may also be provided on the exterior of the sides similar to the strip 22, in Fig. 3. Cushioning material 33 may also be provided on the inner side of the channel similar to that shown in Figs. 2 40 and 3.

In the form shown in Fig. 9, the base member 34 is somewhat wider than the previously described constructions and its edge portions are bent inwardly to form inwardly facing grooves 45 35. The side members are formed as shown in Fig. 7, but, when placed in position, are placed oppositely to the position of Fig. 2, so that the lips 36 at their ends extend into the grooves 35 and are sufficiently loosely engaged therein to 50 permit a slight movement thereof longitudinally of the grooves when the channel is bent. In this instance the base member is shown as covered with textile material 38 and a portion of the outer sides of the side members as partly 55 covered by a narrow strip of similar material 37. Cushioning material for the interior of the channel is provided which is similar to that previously described, except that the material 39 on the base member is extended for the full 60 width of the space between the tongues, to hold the latter in engaged position.

The form of channel shown in Fig. 9 is preferably secured in position by setting one of the base flanges formed by the reversely bent portions, into a groove at one side of the casing groove and securing a removable molding over the other base flange.

In both of the last described forms of my invention the action, when the channel is bent, is precisely the same as that already described in connection with the form first described, the tongues of the sides being moved to slightly radial positions with relation to the curvature of the casing, when the channel is bent to conform 70 thereto, as shown in Fig. 10.

These forms are somewhat advantageous over the first described form in that less sheet metal is required for their construction.

I claim:

1. A window glass channel comprising a base 5 member having longitudinal recesses extending throughout each edge thereof, and a pair of side members each having a continuous edge portion and a series of tongues extending therefrom, the end portions of said tongues being extended transversely into said recesses, slidably to engage said base member.

2. A window glass channel comprising a base member having longitudinal recesses extending throughout each edge thereof, and a pair of side 15 members, each having a continuous edge portion and series of tongues extending therefrom, the end portions of said tongues being bent at right angles to the main portion thereof and extended into said recesses, and means on the base member 20 to retain said end portions in engaged position and permit movement therein longitudinally of the base member.

3. A window glass channel comprising a base member having a reinforcing strip secured thereto 25 on its inner side, said strip having its edge portions off-set from the base member to provide longitudinal recesses at each edge thereof, a pair of side members each having a continuous edge portion and a series of tongues extending therefrom, the end portions of said tongues being extended transversely into said recesses and said base member having an upturned flange at each edge to retain said tongues in engaging position.

4. A window glass channel comprising a base 35 member having its edge portions bent reversely inward, to provide longitudinal recesses at each edge, a pair of side members each having a continuous edge portion and a series of tongues extending therefrom, the end portions of said tongues being extended outwardly and engaged with said base member within said recesses, to permit movement of said end portions therein longitudinally of the recesses, and means on the base member 40 to retain said tongues in engaged position.

5. A window glass channel comprising a base member having its edge portions bent in cylindrical form, a pair of side members, each having a continuous edge portion and a series of tongues extending therefrom and having the end portions thereof bent about said cylindrical edge portions to connect the same thereto and permit 50 slidable movement of the tongues thereon when the channel is bent.

6. A window glass channel comprising a substantially flat base member and a pair of side members disposed approximately perpendicularly thereto and forming substantially the entire sides of the channel, said side members each comprising a continuous edge portion and a series of 60 tongues extending therefrom, the tongues of each side member being slidably connected at their end portions to one edge portion of said base member and arranged to permit a slight movement of the tongues longitudinally of the base member when the channel is bent.

7. A window glass channel comprising a substantially flat base member and separate side members, said side members each comprising a 70 continuous edge portion and a series of parallel tongues extending therefrom, the end portions of the tongues of each side member being bent transversely and connected to one edge portion of the base member, respectively, and arranged 75

to permit movement longitudinally of the base member when the channel is bent.

8. A window glass channel comprising a base member and a pair of separate side members, said side members each comprising a continuous edge portion forming an edge of one side of the channel and a series of tongues extending from said edge portion and forming the remainder of the
- 5 side, said tongues having the end portions thereof bent transversely to connect the same to the edge portions of said base member and arranged at their point of connection to permit a slight movement of said end portions relative to said base member in the direction of its length, when the channel is bent. 5

DAVID C. BAILEY.
